(57) **CLAIM**

The ornamental design for a charging station, as shown and described.

DESCRIPTION

FIG. 1 is a front view of a charging station, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a top, front and right side perspective view thereof. The broken lines shown in the drawings are included for the purpose of illustrating portions of the charging station that form no part of the claimed design.

1 Claim, 7 Drawing Sheets(56)
